US0D1045609S

(12) **United States Design Patent** (10) Patent No.: **US D1,045,609 S**
(45) Date of Patent: ** Oct. 8, 2024

(54) **CAP FOR A CONTAINER**

(71) Applicant: **Chubby Gorilla, Inc.**, Fullerton, CA (US)

(72) Inventors: **Yining Wang**, Hangzhou (CN); **Fengdun Zhang**, Hangzhou (CN); **Xingxin Huang**, Hangzhou (CN); **Ibrahem H. Aboabdo**, Yorba Linda, CA (US)

(73) Assignee: **Chubby Gorilla, Inc.**, Fullerton, CA (US)

(**) Term: **15 Years**

(21) Appl. No.: **29/864,207**

(22) Filed: **May 13, 2022**

(51) LOC (14) Cl. **09-01**

(52) U.S. Cl.

USPC **D9/452**

(57) **CLAIM**

The ornamental design for a cap for a container, as shown and described herein.

DESCRIPTION

FIG. 1 is a top perspective view of a cap for a container showing our new design.

FIG. 2 is a first bottom perspective view thereof.

FIG. 3 is a second bottom perspective view thereof.

FIG. 4 is a front view thereof.

FIG. 5 is a rear view thereof.

FIG. 6 is a first side view thereof.

FIG. 7 is a second side view thereof.

FIG. 8 is a top view thereof; and,

FIG. 9 is a bottom view thereof.

The broken lines in the figures illustrate the portions of the cap for a container that form no part of the claimed design.

1 Claim, 5 Drawing Sheets
